STRIP SERVING MACHINE

Theodore H. Krueger, Stratford, Conn., assignor
to Better Packages Incorporated, a corporation
of New York

Application August 19, 1941, Serial No. 407,411

8 Claims. (Cl. 271—2.3)

This invention relates to strip feeding means, and particularly to intermittent or reciprocating feeding devices such as are used for feeding strips of gummed packaging tape from a roll of tape contained in a dispensing machine. In such machines provision is usually made for serving the tape in desired lengths, and usually for moistening the tape as delivered. The present invention possesses particular utility in such a machine, but it is not limited to use therein.

It is an object of the present invention to provide a tape gripping mechanism which will grip the tape firmly and feed it forward, and which will release the tape so that the feeding device, such as a handle, may be returned to initial position without causing any reverse movement of the tape. The feeding mechanism will again come into gripping relation with the tape upon the next forward movement of the handle, or other actuating means.

It is a further object of the invention to provide a tape gripping and feeding device which will grip the tape in proportion to the resistance to the feed, so that if the resistance increases the tape gripping force increases and positive feeding of the tape will be assured under all normal conditions.

These objects are obtained in general by utilization of the reaction of the feed actuating devices to which the feeding force is applied to bring about or increase the gripping of the tape by the tape feeding elements. Upon movement of the mechanism in reverse direction, the reaction of the forces of the power applying elements release the tape engaging devices from gripping engagement with the tape, so that the tape remains stationary while the parts are reciprocated into position for a second feeding operation.

In the preferred embodiments of the invention the tape is actually gripped and fed by a pair of feed rollers at least one of which is a driving roller and at least one of the rollers is mounted to rotate about a movable axis. The driving force is so applied to the feed rollers that the reaction of such force tends to move the feed rollers into close gripping contact with the tape when the parts are moved in one direction, and to separate the rollers and release such gripping contact when the parts are moved in the opposite direction.

Stated in other words, the machine of this invention translates the energy of the feed handle stroke into two distinct components of motion as opposed to the customary single com-

ponent of motion in prior art machines. These component motions are the rotatory motion of the feed roll shaft and the linear or arcuate motion of the same shaft.

In the accompanying drawings which form a part of this specification are shown certain preferred embodiments of the invention illustrative of the principle thereof. I do not intend to limit myself to the details of such embodiments any further than indicated by the appended claims; on the contrary I intend to include within the scope of such claims the elements defined together with their mechanical equivalents.

In the drawings:

15 Figure 1 is a longitudinal vertical section of a machine embodying the invention, taken on line 1—1 of Figure 2, and parts being broken away;

20 Figure 2 is a transverse vertical section of the machine taken at the position indicated by line 2—2 in Figure 1;

25 Figure 3 is a perspective view of the feeding mechanism, parts being broken away;

30 Figure 4 is a view in longitudinal vertical section of a part of the machine showing an alternative construction; and

35 Figure 5 is a view similar to Fig. 4 showing another alternative construction.

Referring to the form of the invention shown in Figures 1 to 4, 10 is a casing having side walls or frames 11 and 12 between which is a space for a roll of tape 14. In the construction shown the tape passes over a guide roller 16, across a guide plate 17, under a guide roller 18, through a pair of guide channels 19, over a guide plate 20 and over a moistening brush 21 with which the tape is held in contact by movable pressure plate 22. A cut-off knife 24 is indicated diagrammatically in Fig. 1. A weighted knurled member 26, pivoted at 27, is shown for pressing the tape upon the plate 17. This member 26 acts as a ratchet which permits the tape to move in the direction of the arrow, but prevents it from moving in the opposite direction. The particular arrangement and details of the means for guiding the tape may be varied to meet the conditions of use.

In the construction shown the feed means comprise a pair of knurled rolls 30 and 31 adapted to grip the tape strip 32 between them. The roll 30 is shown as mounted on the shaft 35 carried in fixed bearings by plates 11 and 12 and having on its end a driving pinion 37 which is driven by a driving gear 38 mounted on a short shaft 40 to which is affixed an operating crank 41 carrying an operating handle 42. The roll 31

is mounted on a shaft 45 which carries a pinion 47 meshing with a pinion 48 on the opposite end of the shaft 45 from the pinion 37. The shaft 45 is journaled in a swinging yoke or toggle support 50 which is mounted to swing through a limited arc on a shaft 52 mounted in the plates 11 and 12. The relation of the shafts 35, 45, and 52 is such that if the toggle support swings in the direction of the feed of tape, namely, towards the left hand end of the machine as seen in Figure 1, the rolls 38 and 31 are moved into gripping engagement with the tape. When the toggle support swings in the opposite direction, the gripping engagement of the rolls is released. A stop pin 54 is provided for limiting the movement of the toggle support in the latter direction, the maximum movement permitted being insufficient to disengage the teeth of the pinions 47 and 48 which therefore remain in mesh at all times.

In the form of the invention now being described a light frictional resistance to the rotation of the shaft or axle 45, roll 31 and pinion 47 is provided. As illustrated this is produced by a spiral spring 56 mounted on the shaft 45 which engages a brake shoe 57 and holds it against the end of the hub of the roll 31.

The operating crank 41 is moved in the direction of the arrow in Figure 1, that is towards the front of the machine, to produce the feeding movement of the strip. A spring 60 is preferably provided for returning the handle to its initial position against an abutment such as 62, when the feeding operation has been completed and the handle is released.

The operation is as follows: As soon as the operator starts to pull the handle forward the gear 39 starts to rotate the pinion 37, shaft 35, roll 30 and pinion 48. Owing to the slight resistance to rotation of the pinion 47, caused by inertia and bearing friction, supplemented in the construction illustrated by the friction of the brake washer 57, the reaction between the teeth of the pinions 47 and 48 causes the pinion 47 and its shaft or axle 45 to swing the yoke or toggle support 50 to the left (Fig. 1). This swinging movement takes place simultaneously with the initiation of the rotation of the rolls, and as soon as the swinging of the yoke has continued far enough to cause the rolls to engage firmly upon the upper and lower surfaces of the strip, the feeding of the strip begins. Thus the energizing of the feed roll shaft results in two components of motion which are translated to it by a stroke of the feed lever. The strip will thus be gripped between the feed rolls with sufficient tightness to overcome any normal resistance to its movement, and a positively effective feed of the strip is secured. As soon as the handle is moved in reverse direction, or released and permitted to be thrown back by its spring 60, the movement of the gear 39 is reversed with corresponding reversal of rotation of the rolls 38 and 31. However, the immediate effect of such reversal of rotation is to reverse the reaction between the teeth of the pinions 47 and 48 which at once throws the yoke or toggle support 50 towards the right (Fig. 1), thereby separating the rolls and releasing the strip so that the latter remains stationary until the handle is again pulled forward initiating the next feeding operation. An intermittent or reciprocating feed of the strip is thus secured without the use of any pawl and ratchet mechanism, or equivalent device, for permitting the return of the operating handle to

initial position without causing reverse movement of the feed rolls. Danger of over feeding of the strip is avoided, such as may occur if a roll having a ratchet drive were utilized, for in such a case the roll, through its own inertia, would tend to keep on spinning after the feeding stroke had terminated and the handle was released. With the present construction, however, the backward movement of the handle also causes a reverse movement of the rolls, so that there is no chance for the latter to over feed due to their inertia.

Furthermore, provision can be made for taking care of any "bounce" feed which might be caused by the crank flying back under the influence of the spring 60 and striking the abutment 62 with such force as to bounce away from the abutment in the direction of the next feeding stroke. Feeding of the tape can be avoided by providing sufficient clearance between the rolls 38 and 31 so that such rolls will not be brought into gripping engagement with the strip, except upon a movement greater in extent than that caused by the bounce.

Figure 4 shows a modified construction in which the feed roll 70 is mounted on a shaft 71 carrying a pinion 72 which meshes with the teeth on the driving gear 73. In this construction the shaft 71, which is the shaft driven directly by the main driving gear 73, is mounted so as to have a limited movement. In this respect the construction differs from the construction of Figs. 1 to 3 in which the shaft 35 carrying the pinion 37 which meshes with the driving gear 39 is mounted in fixed bearings, and the shaft 45 carrying the roll 31 and the pinion 47, is the shaft mounted on movable bearings.

In the Figure 4 construction the shaft or axle 71 is shown mounted in slots 80 in the side frames or plates 81, the slight movability of the shaft being provided for by means of these slots, instead of mounting the shaft in a swinging yoke. Cooperating with the roll 70, which is capable of bodily, as well as rotary movement, is an idler feed roll 85 which is mounted on a shaft 86 rotating in fixed bearings in the plates 81. When the driving gear 73 is moved in the direction of the arrow in Fig. 4 the reaction of the teeth of the gear against the teeth of the pinion 72 moves the pinion, shaft and roll 71 in the direction of the roll 85 so as to cause the strip to be gripped firmly between the rolls. Continued movement of the driving gear rotates the roll 70 which causes the gripped strip to be fed in the desired manner. If there is any resistance to the movement of the strip such as might be caused by starting the rotation of a large roll of tape, this resistance merely has the effect of increasing the reaction of the teeth of the gear against the teeth of the pinion 72 so that the roll 70 will be forced against the roll 85 more strongly whereby the gripping force of the rolls upon the strip is increased. Reverse rotation of the driving gear 73 produces a reaction upon the pinion 72 which causes the shaft 71 to move away from the shaft 86, thereby releasing the gripping engagement of the rolls 70 and 85 upon the strip.

Fig. 5 shows another slightly modified construction which is similar in operation to that shown in Fig. 4. In place of slots 80 in which the shaft of axle of the movable feed roll is mounted, the movable shaft or axle 90 of the feed roll 91 is mounted in bearings in a pair of arms 92 (only one of which is shown), pivoted on pivots 93. The shaft 90 carries a pinion 95 which meshes

with the main driving gear 96. Cooperating with the movable feed roll 91 is feed roll 97 mounted on a shaft 98 rotating in fixed bearings. As in the construction shown in Fig. 4, the shafts 90 and 98 need not be geared together. The movement of the driving gear 96 in the direction of the arrow produces a reaction upon the pinion 95, shaft 90 and roll 91 causing the latter to grip the strip at the same time that it is rotated. As in the case of the construction shown in Figure 4, resistance to the feed of the tape will result in the rolls gripping the tape more tightly. The reverse movement of the driving gear moves the pinion 95, shaft 90 and arm 92 in a direction to separate the feed rolls, the movement of the arms being limited by a stop 99.

It will be understood that the pivoted yoke or arm mounting and the slotted guide mounting for the movable shaft of one of the feed rolls are alternative constructions, and either may be substituted in either of the modifications shown. Furthermore, the engagement of the driving gear may be with a pinion mounted on either the movable shaft or on the fixed shaft. In the latter event it is necessary to have the two shafts geared together, whereas in the former case it is sufficient if only the movable shaft is positively rotated by the driving gear. In any case it is preferable to provide a friction retarder such as is shown in the Figures 1 to 3 or that the engagement of the gear which drives the pinion on the movable shaft should be at a point in the circumference of such pinion that a reaction will be produced on such pinion tending to move it and the movable shaft in a direction to force the movable roll into gripping engagement with the strip when the driving gearing is moved in a direction to rotate the rolls in strip feeding direction.

While I have illustrated and described in detail certain forms of my invention, I do not wish to be understood as limiting myself to the use of such forms, as I realize that changes within the scope of the invention are possible, and I further intend each element or instrumentality recited in any of the following claims to be understood to refer to all equivalent elements or instrumentalities for accomplishing substantially the same result in substantially the same or equivalent manner, it being my purpose to cover my invention broadly in whatever form its principle may be utilized.

I claim:

1. In strip feeding mechanism, a pair of feed rolls adapted to grip the strip to be fed, one of said rolls being mounted on a displaceable axle, a movable support in which said axle is journaled, a gear on said axle and reversible driving gearing for rotating said gear, said driving gearing when moved in tape advancing direction producing a reaction of said axle gear, axle, movable support and feed roll to cause said movable support to move and bring said feed rolls into gripping engagement with said strip.

2. In strip feeding mechanism, a pair of feed rolls adapted to grip the strip to be fed, one of said rolls being mounted on a displaceable axle, a movable support in which said axle is journaled, a gear on said axle, reversible driving gearing for rotating said gear, and a friction device associated with said displaceable axle for retarding the free rotation thereof.

3. In strip serving mechanism, a pair of feed rolls adapted to grip the strip to be fed between

them, one of said rolls being mounted on an axle journaled in a movable support freely displaceable to a limited extent in a direction to permit separation of the rolls, thereby releasing the gripping engagement between the rolls and the strip, a gear on said axle, gearing for rotating said axle gear, axle and roll carried thereby, said gearing including a main driving gear, manual means for rotating said driving gear in one direction and spring means for rotating said driving gear in the reverse direction.

4. In strip serving mechanism, a pair of feed rolls adapted to grip the strip to be fed between them, one of said rolls being mounted on an axle journaled in a movable support freely displaceable to a limited extent in a direction to permit separation of the rolls, thereby releasing the gripping engagement between the rolls and the strip, a gear on said axle, a relatively large diameter driving gear meshing with said axle gear, manual means for rotating said large diameter gear in a direction to drive said axle gear, axle and roll in a direction to serve the strip, and a spring for returning said handle and large diameter gear to initial position, the reaction of said large diameter gear on said axle gear serving to displace said axle gear, axle, movable support and feed roll to a position to cause said feed rolls to grip the strip and advance the same, the reverse movement of said large diameter gear serving to displace said axle and feed roll thereon sufficiently to release the gripping engagement between the feed rolls and strip so that the strip is not moved in reverse direction.

5. In mechanism for feeding gummed paper strip, a pair of feed rolls adapted to grip the strip to be fed, one of said rolls being mounted on an axle journaled in a displaceable toggle support, and reversible driving gearing for rotating said axle and feed roll thereon, the reaction of said driving gearing displacing said axle and toggle support in one direction or the other depending upon the direction of movement of said driving gear.

6. In strip feeding mechanism a pair of feed rolls adapted to grip the strip to be fed, one of said rolls being mounted on an axle displaceable in parallel relation to the axis of rotation of the other roll, a gear on said axle and reciprocatable power applying means for driving said gear.

7. In strip feeding mechanism a pair of feed rolls adapted to grip the strip to be fed, one of said rolls being mounted on a displaceable axle, a movable support in which said axle is journaled, said support engaging said axle on either side of said roll and being itself pivoted on an axis parallel to the axis of the other feed roll, a gear on the displaceable axle, reversible driving gearing for rotating said gear and means to prevent said gear on said axle and said reversible driving gear from losing meshing contact.

8. In strip feeding mechanism, a pair of feed rolls adapted to grip the strip to be fed, one of said rolls being mounted on an axle displaceable in position parallel to the axis of the other feed roll, a gear on said axle, a reciprocal driving gearing for rotating said gear means to limit the displacement of said axle to maintain the meshing of said gear and a friction device associated with said displaceable axle for retarding the free rotation thereof.

THEODORE H. KRUEGER.
